(57) **CLAIM**

The ornamental design for a handle for a utensil, as shown and described.

DESCRIPTION

FIG. 1 is a top plan view of a handle for a utensil according to the design;

FIG. 2 is a right side elevational view thereof;

FIG. 3 is a bottom plan view thereof;

FIG. 4 is a left side elevational view thereof;

FIG. 5 is a first end elevational view thereof;

FIG. 6 is a second end elevational view thereof;

FIG. 7 is a cross-sectional view taken along line 7—7 of FIG. 1;

FIG. 8 is a top plan view of an alternative embodiment handle for a utensil according to the design;

FIG. 9 is a right side elevational view thereof;

FIG. 10 is a bottom plan view thereof;

FIG. 11 is a left side elevational view thereof;

FIG. 12 is a first end elevational view thereof;

FIG. 13 is a second end elevational view thereof;

FIG. 14 is a cross-sectional view taken along line 14—14 of FIG. 8;

FIG. 15 is a top plan view of an alternative embodiment handle for a utensil according to the design;

FIG. 16 is a right side elevational view thereof;

FIG. 17 is a bottom plan view thereof;

FIG. 18 is a left side elevational view thereof;

FIG. 19 is a first end elevational view thereof;

FIG. 20 is a second end elevational view thereof;

FIG. 21 is a cross-sectional view taken along line 21—21 of FIG. 15;

FIG. 22 is a top plan view of an alternative embodiment handle for a utensil according to the design;

FIG. 23 is a right side elevational view thereof;

FIG. 24 is a bottom plan view thereof;

FIG. 25 is a left side elevational view thereof;

FIG. 26 is a first end elevational view thereof;

FIG. 27 is a second end elevational view thereof; and,

FIG. 28 is a cross-sectional view taken along line 28—28 of FIG. 22.

The broken lines shown in FIGS. 1—4, 8—11, 15—18 and 22—25 are illustrative of environmental structure only and form no part of the claimed design.
